UNITED STATES PATENT OFFICE.

EDWARD P. RICH, OF CHICAGO, ILLINOIS.

SYSTEM OF TEMPERATURE CONTROL.

Application filed October 1, 1920. Serial No. 414,018.

To all whom it may concern:

Be it known that I, EDWARD P. RICH, a citizen of the United States, residing at Chicago, in the county of Cook and State of Illinois, have invented a certain new and useful Improvement in Systems of Temperature Control, of which the following is a specification.

My invention relates to systems of temperature control, and the object is to provide sure-acting and sensitive means for controlling a steam radiator or similar heating element. I obtain these objects by the mechanism illustrated in the accompanying drawings in which—

Figure 1 is a general side elevation partly in axial section showing the radiator and the complete control mechanism;

Figure 2 is a fragmentary detail showing the different positions of the pilot or bypass valve.

Like numerals denote like parts in both views.

In the particular form selected to illustrate the invention steam is led to the radiator 1 through a steam supply pipe 2. A return pipe 3 leads the steam and condensed moisture back to the boiler. By preference the return pipe is maintained under a low vacuum. It is desirable, although not necessary, to provide a steam trap at the radiator outlet 4. A standard device is illustrated in which the body 6 of the trap has a valve seat 7 adapted to cooperate with a valve 8, and a "bellows" or expansion element 9 is mounted in the body 6 and actuates valve 8. In the presence of steam the bellows expands and holds the valve closed, whereas if the temperature drops and moisture collects, the bellows will contract and open the valve. The parts as thus far described are standard and well known, and the design may be varied without departing from the spirit of the invention.

Considering now more particularly the parts involved in the present invention: The entrance of steam from pipe 2 to the radiator is controlled by a main valve 12 which cooperates with a valve seat 13. The valve stem 14 which controls the valve 12 passes

out through a stuffing box 16 and into a control chamber 18 where it is attached to and operated by a thermo-sensitive bellows or expansion element 20. The construction is such that when bellows 20 is in the presence 55 of steam it will expand and close the main valve 12. In the absence of steam, when the temperature falls, the bellows will contract and open the valve. In order to prevent leakage from the control chamber, it is desirable to have the stem 14 pass out through a packless valve 22 which is simply a collapsible steam tight structure of well known type which permits the stem to rise and fall and operates with practically no friction. 60

The steam supply to the control chamber 18 is supplied by a bypass 24 which leads from steam supply pipe 2 directly to the control chamber, passing around the main valve 12. In this bypass are located two 70 valves, viz, a needle valve 26 which is hand controlled and a bypass or outlet valve 28 which is controlled thermostatically. The parts are so constructed that the pilot valve stands open when the main valve is closed, 75 thus permitting a constant flow of steam under such conditions; and the purpose of the needle valve 26 is to enable the attendant to reduce this flow to the lowest degree at which the system will operate, thereby reducing the steam consumption for control purposes to a minimum.

As intimated, the pilot or master valve 28 is controlled thermostatically, and according to the present design the mechanism consists 85 of an expansion bellows or other form of thermostat 30, in the present case housed within a chamber 32 and located for convenience beneath the radiator. It is desirable, in order not to have the thermostat too 90 greatly influenced by the direct heat of the radiator, to encase the chamber in a jacket 34 of insulating material. Fastened to and operated by the thermostatic element 30 is a rod 36 which is pivotally connected to the 95 free end of a lever 38 which actuates valve 28. When the room temperature, to which the thermostat is subject, exceeds the predetermined maximum temperature, the thermostatic element 30 expands, thus moving 100

the pilot valve from closed position shown in Figure 1 to open position, shown in full lines in Figure 2. Conversely, when the room temperature falls below such degree, 5 the thermostatic element contracts and moves the pilot valve to closed position shown in Figure 1.

An outlet pipe 40 leads from control chamber 18 to the vacuum return pipe 3 beneath the steam trap 6. It is desirable to furnish this with a hand operated needle valve 42 and with a strainer 44. The attendant by properly adjusting valve 42, especially with reference to the position of 15 valve 26, can control the amount of steam which will accumulate in the control chamber when the pilot valve is open. It is evident that by keeping valve 42 nearly closed and valve 26 wide open there will be a tendency for steam to accumulate in the control 20 chamber when the pilot valve is open. This accumulated steam would tend to keep the main valve closed for a greater proportion of the time than if valve 42 were kept wide 25 open and valve 26 nearly closed. As there is a vacuum in the return pipe 3 and outlet or drain pipe 40, it is evident that if valve 26 were nearly closed and valve 42 were wide open, the tendency would be to keep 30 the control chamber free of steam and hence the main valve 12 would be held open for a greater proportion of the time.

The principle of operation will now be readily understood. So long as the room 35 temperature remains below the predetermined maximum, the thermostatic element 30 will hold the pilot valve 28 closed, thus cutting off steam supply to the control chamber 18 and causing the pilots 20 to hold the 40 main valve open. This enables the radiator to warm the room and maintain the desired degree of temperature in it. As soon as the room temperature exceeds the predetermined maximum the thermostatic element 30 expands and opens the pilot valve 28, thus admitting steam to the control chamber 18 and causing the bellows 20 to expand and close the main valve 12. As long as the room thus 45 remains overheated, the main valve will remain closed, but there will be a slight flow of steam through the bypass 24. The amount of steam consumption for control purposes is practically negligible, it being possible by regulating properly the valves 50 26 and 42 to gain the desired results by an almost inappreciable amount of steam. Among the other advantages of my apparatus is that it is compact and all parts may be located practically at the radiator itself. 55 Another advantage is that the construction is simple and that the moving parts are actuated by well known and standard elements that are positive and forceful in their operation. Furthermore, the apparatus requires 60 no particular equipment in the radiator it-

self, but is in the nature of an attachment and therefore may be applied to old installations as well as new.

Having thus described my invention, what I claim as new and desire to secure by Letters Patent is:

1. In a heating system, the combination of a radiator, a steam supply pipe leading thereto, a main shut-off valve for controlling the steam supply, a control chamber, a thermo-sensitive element in said control chamber adapted to actuate said valve and close the same when said element is heated, a bypass leading from the steam-supply pipe, on the supply side of the main shut-off valve, to said control chamber, a master valve in said bypass, a thermostat for controlling said master valve, and means for exerting constant suction from said control chamber, whereby when the master valve is closed the hot vapor will be promptly withdrawn from the control chamber to enable the thermo-sensitive element to cool promptly, and when the master valve is open the steam will be induced to flow promptly from the bypass into said control chamber to hasten the heating of said thermo-sensitive element.

2. In a vacuum heating system, the combination of a radiator, a steam supply pipe leading thereto, a main shut-off valve for controlling the steam supply, a control chamber, a thermo-sensitive element in said control chamber, adapted to actuate said valve and close the same when heated, a bypass leading from the steam supply pipe on the supply side of the main shut-off valve to said control chamber, a master valve in said bypass, a thermostat for controlling said master valve, a vacuum return pipe leading from the radiator, and a pipe leading from said control chamber to said vacuum return pipe.

3. In a vacuum heating system, the combination of a radiator, a steam supply pipe leading thereto, a main shut-off valve for controlling the steam supply, a control chamber, a thermo-sensitive element in said control chamber adapted to actuate said valve and close the same when heated, a bypass leading from the steam supply pipe on the supply side of the main shut-off valve to said control chamber, a master valve in said bypass, a thermostat for controlling said master valve, a vacuum return pipe leading from the radiator and a pipe leading from the bottom of said control chamber to said vacuum return for inducing flow into said chamber and also positively withdrawing therefrom both vapor and water of condensation.

4. In a heating system having a radiator provided with a steam supply pipe, a vacuum return pipe and a main valve for controlling the flow of steam to the radiator; a control chamber having a thermo-sensitive ele-

ment for controlling the main valve, a bypass leading from the steam supply pipe to the control chamber, a drain pipe leading from the control chamber direct to the 5 vacuum return pipe for sucking steam and moisture out of the control chamber, a thermally controlled pilot valve in said bypass, and manually controlled regulating valves

in said bypass and in said drain pipe whereby the attendant by properly adjusting said 10 regulating valves can vary the heat conditions in said control chamber.

In witness whereof, I have hereunto subscribed my name.

EDWARD P. RICH.
